(57) **CLAIM**

The ornamental design for an outdoor lighting system transformer, as shown and described.

DESCRIPTION

FIG. 1 is a perspective view of an outdoor lighting system transformer showing my new design;

FIG. 2 is a front side elevational view thereof;

FIG. 3 is a back side elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front perspective view thereof, shown in an alternate configuration.

The portions shown in broken lines form no part of the claimed design.

1 Claim, 7 Drawing Sheets
